STABILIZED ORGANIC SULFUR-CONTAINING COMPOUNDS

Theodore J. Peters, Jr., Somerville, N. J., assignor to Esso Research and Engineering Company, a corporation of Delaware

No Drawing. Application May 13, 1952,
Serial No. 287,605

3 Claims. (Cl. 260—137)

This invention relates to an improved method of minimizing the evolution of hydrogen sulfide from organic sulfur-containing compounds from which hydrogen sulfide is normally evolved.

Many organic sulfur-containing compounds normally evolve hydrogen sulfide during storage, transportation or use. Because of the obnoxious odor of the hydrogen sulfide gas, this evolution is quite objectionable. Frequently, it is desired to use such compounds as additives for mineral oil compositions, such as lubricating oils, to impart to the composition various desired properties such as extreme pressure properties, anti-corrosive properties, detergent properties and the like. However compositions containing even small amounts of unstable sulfur-containing compounds will evolve hydrogen sulfide. Users of such compositions object to these odors, and consequently the saleability of the product is impaired. Many organic compounds that have been sulfurized by treatment with sulfur, sulfides of phosphorus and the like show this characteristic instability with respect to hydrogen sulfide evolution.

Numerous attempts have been made to stabilize such sulfur-containing compounds or compositions including these compounds. Neutralization of acidic sulfur-containing materials with basic reagents frequently fails to give a stable product. In some cases, inhibitors have been added which tend to minimize H₂S evolution. Another procedure that has wide spread usage involves blowing the material with air in order to stabilize the material against H₂S evolution. Treatment with air, however, is costly and time consuming because extensive treating is required to form a fairly stable product. Frequently, treating times of 1 to 3 days or more are required even at high air rates. Treatment with oxygen or gases containing high concentrations of oxygen is very dangerous due to explosion hazards existing with even small amounts of hydrocarbons. Furthermore, the air-treated material often proves to be unstable when it is heated to elevated temperatures in subsequent use. It is an object of the present invention to provide a rapid, safe, effective stabilizing method that overcomes the disadvantages of air blowing and eliminates or minimizes the need of using expensive additives for inhibiting H₂S evolution.

In accordance with the present invention, liquid organic sulfur-containing compounds are treated with a relatively small amount of an oxide of nitrogen such as nitric oxide, nitrogen dioxide, nitrogen trioxide, nitrogen tetroxide, nitrogen pentoxide and their mixtures. A mixture of nitric oxide and nitrogen dioxide is particularly suitable. Briefly, the liquid material to be treated is contacted with the vaporous oxide of nitrogen in an amount sufficient to eliminate or minimize subsequent H₂S evolution but insufficient to cause a substantial loss in total sulfur content. The treating step may be carried out at atmospheric temperature and pressure conditions, although temperatures such as in the range of about 50° up to 250° F. and higher may be used to obtain more complete

2

treating. The treatment should be carried out in the substantial absence of water to avoid formation of acids of nitrogen.

The reason for the effectiveness of oxides of nitrogen for stabilizing the sulfur-containing organic compounds is not entirely understood, and it is not desired to be bound by any theory of action. The treatment is carried out under conditions such that substantially no sulfur is removed from the material being treated, but loosely bound or unstable sulfur is evidently affected in some manner. Apparently, the oxide of nitrogen reacts to some extent with the material being treated, and perhaps in this way forms stable compounds that will not subsequently decompose to H₂S. It is possible that unstable thiol groups are converted to stable disulfides. The amount of oxide of nitrogen needed to stabilize the material is so small, however, that any chemically bound nitrogen remaining in the treated product is not deleterious. In some cases, the nitrogen entering the treated compounds seems to be beneficial when the sulfur-containing material is used as a lubricant anti-oxidant or the like.

In carrying out the process, any suitable apparatus permitting intimate contact between the material being treated and the oxide of nitrogen may be used. For example, the oxide of nitrogen may be passed upwardly through a packed tower in countercurrent relationship with down-flowing sulfur-containing compound, the tower being of the conventional scrubber type containing Raschig rings, disc and donut contactors, and other types of packing. If desired, the gas may be blown into a tank containing the material to be treated, and the material may be agitated by a stirrer or other type of agitating device. Such contacting devices are well known to the art.

In the event the sulfur-containing organic compound is extremely viscous, improved contacting may be obtained by operating at elevated temperatures as heretofore mentioned or by diluting the material to be treated in a suitable solvent that will lower the viscosity thereof. For example, if the material is to be used as a lubricant additive, it may be dissolved in a lubricant base stock and the blend treated as described above. The solvent may be of a different boiling point so that it may be easily separated in a subsequent distillation operation. The oxide of nitrogen may be used in a relatively pure form, although ease of handling may be improved by employing a blend of an inert gas such as nitrogen, carbon dioxide and the like, containing about 5% or more of the oxide. The oxide of nitrogen may also be blended with air, and the air-nitrogen oxide mixture used for treating the unstable material. The oxide of nitrogen may be generated by any suitable means well known to the art, and the gaseous oxide should be substantially free of water or acids of nitrogen.

The amount of oxide of nitrogen needed to effect stabilization will vary depending on the type of material being treated, the efficiency of contact during the treating step, treating rates, treating temperatures and other conditions. The amount may be as low as about 0.1 cubic foot per hour per gallon of sulfur-containing material being treated providing the contact time is sufficient. Generally, rates in the order of about 3 to 100 cubic feet of vaporous oxide of nitrogen per hour per gallon of liquid feed will be sufficient to effect stabilization. Under these conditions, contact times may range from about 5 minutes up to one to ten hours or more.

The present invention has particular application to the improvement of sulfurized organic compounds prepared by treating organic compounds with sulfur, sulfides of phosphorus, such as phosphorus pentasulfide and phosphorus sesquisulfide, etc., their mixtures and other

sulfurizing agents well known to the art. The organic compounds that are sulfurized are also well known to the art. These include the hydrocarbons such as olefins, olefin polymers, diolefins, acetylenes, aromatics, petroleum fractions such as lubricant distillates, residua, petrolatums, and the like. Terpenes such as dipentene, pinenes, and the like are also sulfurized to form effective lubricant additives and the like, the products generally being unstable.

Other organic compounds that may be sulfurized include the organic acids, particularly the higher carboxylic acids, esters, petroleum acids, naphthenic acids, higher alcohols, ketones and aldehydes, and other oxygen containing compounds. Phenols such as the alkyl phenols, alkyl phenol sulfides and the like are particularly valuable as feed stocks for sulfurization to make lubricant additives. Other organic compounds include amines, fatty oils of animal and vegetable origin such as sperm oil, degras, and the like.

Frequently, the acidic sulfurized organic material is treated with a basic material for neutralization purposes or to introduce a metal component into the material. The treatment of the present invention may be applied before neutralization. It is also effective in preventing H₂S evolution from neutralized materials in those cases where the neutralized compound evolves H₂S as heretofore described. It is also known that sulfurization of metal salts of organic compounds produces unstable materials. Treatment of such materials with an oxide of nitrogen is also quite effective.

The improved products of the present invention may be used as additives for mineral oils such as lubricating oils, greases, heating oils, gasolines and the like. Amounts in the range of about 0.01 to 10% by weight may be used depending on the property of the composition to be improved. The stable agents find use as antioxidants and corrosion inhibitors, extreme pressure additives, detergents, sludge dispersers and the like. When the sulfurized materials treated in accordance with the present invention are used in such compositions, the resulting blends have substantially no tendency to evolve H₂S even when subjected to elevated temperatures.

As heretofore mentioned, the sulfurized organic compound may be diluted before treatment. Thus, a lubricant base stock containing in the range of about 20 to 50% by weight of the unstable compound may be treated with an oxide of nitrogen as described above. The treated concentrate is then stored and shipped in that form. A finished lubricant is prepared by blending the needed amount of the concentrate with a lubricant base stock to obtain any desired concentration. The finished lubricant may comprise, in addition to the treated sulfur-containing material, other additives well known to the art such as viscosity index improvers, detergents, etc.

The practice of the present invention will be illustrated in connection with the following examples, although the invention is not to be construed as being limited by these examples in any way.

EXAMPLE I

The product resulting from treating barium tert.-octyl phenol sulfide with 4% by weight of phosphorus pentasulfide was treated with a blend of nitric oxide (NO) and nitrogen dioxide (NO₂) in accordance with the present invention. A series of runs were carried out in which the phosphosulfurized material was placed in a flask equipped with a stirrer, and the dry gaseous mixture was bubbled into the stirred material. The treated material was held at a temperature of 122° F. The oxides of nitrogen were charged at various rates with total contact times varying from about 3 to 11 minutes. In each case, the treated material was blown with air in order to insure removal of any free Na₂O₃, about 100 volumes of purge air per volume of treated material

being employed in each run. After the air purge was completed, the product was heated to a temperature of about 212° F. and then filtered thru a diatomaceous earth filter aid.

The product from each run was then tested for H₂S evolution tendencies. This was carried out by the following procedure:

800 mls. of the blend to be tested were placed in a small-mouth 1 quart bottle. An aluminum foil covered stopper was placed in the mouth of the bottle and the contents raised to 100° F. for 1 hour. At the end of this period, a filter paper wet with a saturated solution of aqueous lead acetate was placed over the mouth of the bottle and allowed to remain for 5 minutes. The filter paper was removed and the extent of staining compared with a standard.

The extent of staining of the paper is rated on a scale of from 0 (no staining) to 10 (complete black sulfide film). The material is considered to have a satisfactory stability if the H₂S rating is below about 6. A D. N. P. (Did Not Pass) is given when the rating is above about 6. The untreated product gave a D. N. P. rating. The results of the runs are shown in Table I below:

Table I
TREATMENT OF PHOSPHOSULFURIZED BARIUM ALKYL PHENOL SULFIDE WITH NO-NO₂ MIXTURES

Run No.	Treating Conditions			
	NO-NO ₂ Rate, Cu. Ft./Hr./ Gallon	Time, Minutes	Temp., °F.	H ₂ S Rating on Product
A	22.2	3	122	D. N. P.
B	19.2	10	122	Pass.
C	15.5	5	122	D. N. P.
D	11.3	11	122	Pass.

Under the conditions employed, treating times of from 3 to 5 minutes with NO-NO₂ rates of about 15 to 22 cubic feet per hour per gallon were insufficient to form a satisfactory product. NO-NO₂ rates of from about 10 to 20 cubic feet per hour per gallon with treating times of about 10 minutes were sufficient to form a product having excellent H₂S stability. In contrast, several runs were carried out in which air was employed as the contacting agent. At an air rate of 5.3 cubic feet per hour per gallon, 43 hours' treating time was needed to form a satisfactory product. At an air rate of 75 cubic feet per hour per gallon, 17 hours' treating time was necessary to form a product passing the H₂S evolution test. The time required to stabilize with air was more than an order of magnitude greater than the time required when using an oxide of nitrogen.

Comparative analysis of feed and product from Run B (Table I) are shown in Table II below:

Table II
ANALYSIS OF FEED AND PRODUCT, RUN B

Component, wt. percent	Feed	Treated Product
Barium	8.37	8.31
Sulfur	5.82	5.73
Phosphorus	0.967	0.983
Nitrogen	0	0.25

It is seen that the total barium, sulfur and phosphorus contents of the material were substantially unaffected and that a small amount of chemically bound nitrogen remained in the product. It was also found that the nitrogen oxide treatment did not impair the effectiveness of the product from Run B as a lubricant additive from the standpoint of bearing corrosion inhibition properties and copper strip staining properties. Indeed, the corro-

sion inhibition properties of the treated material were somewhat superior to those of both the untreated and the air-blown materials.

EXAMPLE II

A sample of sulfurized dipentene, which had an H₂S rating of 10+ was treated with an NO—NO₂ mixture at a rate of about 9.0 cubic feet per hour per gallon for 17 minutes. An H₂S rating of 0 was obtained on the treated product. The treatment was carried out under substantially the same conditions employed in Example I. A lubricating oil containing 2.5% by weight of the untreated sulfurized dipentene did not pass the H₂S evolution test. An oil blend containing 2.5% by weight of the sulfurized dipentene treated with the oxides of nitrogen gave an H₂S rating of 0.

What is claimed is:

1. In a method for preparing organic sulfur-containing compounds useful as lubricating oil additives and selected from the group consisting of sulfurized hydrocarbons and phospho-sulfurized metal salts of alkyl phenol sulfides, the improvement in accordance with which the odor of said organic sulfur-containing compounds is improved which consists essentially of contacting said organic sulfur-containing compounds selected from the group consisting of sulfurized hydrocarbons and phos-

pho-sulfurized metal salts of alkyl phenol sulfides with a vaporous oxide of nitrogen at a temperature of about 50° to 250° F. for about 5 minutes to 1 hour to thereby substantially reduce the evolution of hydrogen sulfide from said organic sulfur-containing compound without removing substantially any sulfur therefrom, said contacting being carried out in the substantial absence of water and employing about 3 to 100 cubic feet of vaporous oxide of nitrogen per hour per gallon of said organic sulfur-containing compound.

2. A method as in claim 1 wherein said oxide of nitrogen is a mixture of NO and NO₂.

3. A composition as in claim 1 wherein said sulfurized organic compound is a phosphosulfurized barium salt of an alkyl phenol sulfide.
